CABINET CONSTRUCTION

Eugene J. Smayda, Jr., University Heights, Ohio

Application August 6, 1949, Serial No. 108,919

10 Claims. (Cl. 312—350)

1

My invention relates to cabinets, compartments and racks for supporting and accommodating a plurality of trays and the like.

The present invention is related in subject matter to my Patent No. 2,503,599, dated April 11, 1950.

An object of my invention is to provide an improved cabinet for accommodating a plurality of trays and the like, the cabinet being economical to manufacture and efficient in use.

Another object is to provide a novel structure in a cabinet for accommodating a plurality of trays and having a minimum of structural elements embodied therein.

Another object is the provision of an improved construction in a cabinet of the class described and providing rigidity to the cabinet by an efficient and economical arrangement.

Another object is the provision of an improved construction in a cabinet for the assembly of the side walls to framing members at the open front of the cabinet.

Another object is the provision of a cabinet having sheet metal sides formed with channels therein and having the side walls disposed in one plane at the ends of the channels.

Another object is the provision of a construction for a cabinet in which the corrugated side walls are flattened at the forward edge of the side walls to position the side walls at the front edge in one vertical plane.

Another object is the provision of a cabinet which is formed with channels in the side walls and which has the side walls arranged for easy and ready insertion and withdrawal of the trays in the channels.

Another object is the provision of a cabinet construction that is sanitary in use and obviates the lodgment of food particles or foreign matter in portions of the side walls.

Another object is the provision of a unique arrangement for forming and assembling the portions of a cabinet.

Another object is the provision of an improved cabinet arranged to provide results not heretofore obtainable.

Another object is the provision of an improvement in the construction of parts of the cabinet shown in my said co-pending application.

Other objects and a fuller understanding of my invention may be had by referring to the following description and claims, taken in conjunction with the accompanying drawings, in which:

Figure 1 is a side view of a cabinet embodying my invention;

2

Figure 2 is a cross-sectional view of my cabinet looking in the direction of the arrows 2—2 of Figure 1;

Figure 3 is an enlarged sectional view of a portion of my cabinet looking in the direction of the arrows 3—3 of Figure 1;

Figure 4 is an enlarged sectional view of a portion of my cabinet looking in the direction of the arrows 4—4 of Figure 1; and

10 Figure 5 is an enlarged sectional view of a portion of my cabinet looking in the direction of the arrows 5—5 of Figure 1.

A general description of the class of cabinets in which my invention resides and of the uses of

15 such cabinets is given in my said Patent No. 2,503,599. My cabinet has sheet metal side wall members denoted generally by the reference character 11. These side wall members 11 are

spaced apart parallel to each other to form the 20 two side walls of the cabinet. Fitting over the top and enclosing the upper end of the cabinet is a top wall 12 having peripheral flanges 12-a extending down and overlapping the upper edges of the cabinet walls. A rear wall 13 is joined to

25 the rear vertical edges of the side walls 11 to enclose a third side of the cabinet. Vertical flanges 13-a, which are doubled back and disposed at right angles to the body of the rear wall 13, overlap and are joined to the side wall members 11 at the rear vertical edges thereof.

A bottom wall member 14 is disposed horizontally 30 at the bottom end of the cabinet and is secured thereto to enclose the bottom end of the cabinet. The remaining open side of the cabinet is adapt-

35 ed to be closed by a door 17 hingedly carried by the cabinet and adapted to be swung open to provide access to the interior. The walls 11, 12, 13,

14 and the door 17 are preferably all formed of 40 sheet metal and form an enclosure for a plurality of trays, which may contain food or other mate-

rial thereon supported in place by the side walls 11. Suitable casters 19, carried on swiveled brackets 18, are secured to the bottom of the cabinet to provide ready mobility of the cabinet.

45 The two opposite side walls 11 have oppositely facing channels 11-a formed therein by pressing, bending or other suitable operation. The channels 11-a are disposed to accommodate the edges of trays, which may be slid into the cabinet from

50 the front thereof. To form the channels 11-a in the sheet metal wall members, the wall members are provided with a web portion 11-b forming the inner wall of the respective channels. This web portion 11-b of the several channels in

55 each wall member is disposed in one vertical

plane. Between the several channels in each wall member, there is a connecting portion 11-c which determines the spacing between the channels. These connecting portions 11-c between the several channels of a wall member are all disposed in a second vertical plane spaced from, and parallel to, the first vertical plane, as best illustrated in Figure 5. Where the channels are formed, that is, in the main body portion of the wall members, the sheet metal is in a corrugated or recurrently angular form. This provides a reversed channel or outer open space adjacent the connecting portion 11-c. If the connecting portions 11-c were continued throughout the depth of the cabinet, then these open spaces adjacent the connecting portion 11-c would be presented at the front and rear edges of the side walls. However, in the present invention, the connecting portions 11-c at the front and rear edge portions of the wall members are flattened or drawn in to the same vertical plane in which the web portions 11-b are disposed. As shown in Figures 3 and 4, the connecting portions 11-c are drawn or moved in a gradual slope to where they coincide with the same vertical plane as the web portions 11-b. Thus, at the front and rear vertical edge portions of the wall members, all of the material of the wall members is in one vertical plane. Likewise, the outer open spaces adjacent the connecting portions 11-c at the front and rear edges are eliminated. This helps prevent the lodgment of food particles or foreign matter in these open spaces and a neat and smooth surface is presented at the interior of the cabinet. The edges of the wall members look neater and there are no sharp wavy edges that may be encountered when the door 17 is opened. The correct location of the channels 11-a is more apparent so that the insertion of trays in their proper place is facilitated.

At the front vertical edge of the respective side wall members a framing is provided by the framing members 15. Each framing member 15 has a grooved or recessed portion 15-a disposed longitudinally of the framing member. This grooved portion 15-a is dimensioned to accommodate and embrace or bind the front edge portion of the side wall member, which front edge portion is denoted by the reference character 16. As best illustrated in Figure 4, the grooved portion 15-a extends around on both sides of the front edge portion 16 and covers the extreme front edge of the portion 16. The frame member 15 has a body portion 15-b which is displaced away from the cabinet and from the first vertical plane in which the portion 16 is located. The body portion 15-b in the assembly shown is disposed to extend out at an angle from the side wall member and thence extends back toward the side wall member where it terminates. The flat portion 15-c is disposed to be adjacent to the web portion 11-b disposed in the said first vertical plane and the flat portion 15-c extends longitudinally of the framing member and vertically of the cabinet. Suitable welds 23 disposed at intervals along the length of the framing member 15, weld the flat portion 15-c to the side wall member at various locations from top to bottom of the cabinet. By the binding of the front edge portion 16, by the grooved portion 15-a, and by the welding of the flat portion 15-c to the wall member at various locations, each framing member 15 is firmly secured to a respective wall member. The disposition of the body portion 15-b is such as to provide rigidity to the framing member and to the wall member to

which it is secured. The framing members provide a frame upon which the door 17 may be attached. Suitable hinges on one framing member support the door 17 and a suitable latch, such as latch 27, secures the door 17 to the other framing member. The door 17 has its vertical edges closely abutting against the framing members when the door is closed.

A threaded bolt or stud 20 is positioned in the space between the wall member and the body portion 15-b, near the lower end of each framing member 15. The threaded bolt or stud 20 is secured to the framing member by a weld 21. The threaded end of the stud 20 extends downwardly and is threadably engaged by a nut 24. The nut 24 threaded on the bolt 20 firmly secures the framing member 15 on each side of the cabinet to the bottom wall 14. There is a threaded bolt at the lower end of each of the framing members and the bottom wall 14 is similarly secured to the framing members on the opposite sides of the cabinet.

At the rear vertical corners of the cabinet, the wall member is similarly disposed in the first vertical plane so that the channels extend between the front and rear vertical edge portions. The rear vertical edge portions of the wall members, respectively, are secured to the flanged portions 13-a of the rear wall 13 by suitable welds 22, as indicated in Figure 3. The welded connections 22 between the side wall members and the flanged portions 13-a are positioned at suitable intervals along the vertical extent of the wall members at the rear corners of the cabinet. By this construction, a strong and rigid corner is provided to the cabinet and without the use of additional framing or external support. The flanged portions 13-a of the rear wall member form a strong framing element in themselves. Likewise, by the arrangement and the use of the channeled configuration of the side wall members, lateral or vertical bracing members are obviated. A lightweight and yet strong and rigid construction is thus provided.

At each of the rear corners of the cabinet and adjacent the bottom wall 14, a triangular piece of metal 25 is welded or otherwise secured to the rear wall 13 and the side wall 11, in the position shown in Figure 3. A triangular piece 25 is positioned and secured in each of the rear corners of the cabinet. These triangular pieces are thus carried between the rear and side walls of the cabinet. A nut and bolt assembly 26 engaged in a suitable hole in the triangular piece 25 secures the triangular piece 25 to the bottom wall 14 of the cabinet. A nut and bolt assembly 26 is in each rear corner of the cabinet to secure, through the triangular pieces, the rear wall and side walls to the bottom wall. Thus, by the nut and bolt assemblies 26 and the threaded bolts 20, with their respective nuts 24, the four corners of the cabinet are secured to the bottom wall.

The above described and shown construction provides for the ready assembly and joinder of the parts of the cabinet also provides for a lightweight and simple connection. The form of the parts and particularly of the front edge portions, bound or embraced by the framing members, provides an improvement in the strength, use and appearance of the cabinet. Other advantages and benefits are obvious from the inspection and consideration of the construction shown.

The present disclosure includes by reference herein the description contained in the appended claims.

Although my invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed:

1. In a cabinet, the construction comprising a pair of sheet metal side wall members disposed parallel to each other and spaced from each other to provide the side walls of the cabinet, each side wall member being recurrently bent at intervals to form a plurality of horizontally disposed and parallel channel portions and a plurality of connecting portions alternating with and joining the channel portions, said channel portions of each side wall member having web portions disposed in a first vertical plane and said connecting portions of each said side wall member being disposed in a second vertical plane spaced from said first vertical plane inwardly of said cabinet, each side wall member adjacent the forward edge thereof having said connecting portion displaced from said second vertical plane to a plane substantially coinciding with said first vertical plane, and a metallic framing member disposed vertically and adjacent each said side wall member at said forward edge, said framing member having a longitudinal grooved portion embracing the forward edge portion of the respective side wall member disposed in said first vertical plane, said framing member having a body portion joined to said grooved portion and extending outwardly of the cabinet away from, and thence toward, said first vertical plane to provide rigidity to said framing member and having a flat portion joined to said body portion and disposed adjacent the said web portion of the side wall member in said first vertical plane, said framing members enclosing the forward edges of the respective side wall members and imparting rigidity and strength to the side wall members at said forward edges.

2. In a cabinet, the construction comprising sheet metal side members disposed in parallel and spaced relationship to each other to provide the side walls of the cabinet, said side wall members being corrugated to provide horizontally disposed channels on the inner faces thereof and to provide rigidity to the wall members in one dimension of the cabinet, said side wall members each having a front edge portion defining a doorway of the cabinet, and a metallic framing member for each said front edge portion, each said framing member having formed therein a grooved portion disposed vertically and along a said front edge portion, each said side wall member at the front edge portion thereof being flattened to coincide with one vertical plane and being disposed in, and embraced by, a said grooved portion, each said framing member having a flat portion spaced rearwardly from said grooved portion and joined to said side wall member at said vertical plane, each said framing member also having a body portion joining said grooved portion and flat portion, said body portion being displaced outwardly of the cabinet from said vertical plane to provide rigidity in a second dimension of the cabinet to the framing member and to the side wall member at said forward edge portion.

3. In a cabinet, the construction comprising

opposite and spaced sheet metal side wall members, each said side wall member being recurrently bent back upon itself to provide horizontal channels inwardly of the cabinet bounded by a first vertical plane and a second vertical plane parallel to the first vertical plane, said side wall members at the front and rear edge portions thereof being disposed in a first of said vertical planes and said channels extending horizontally intermediate of said front and rear edge portions, and metallic framing members for the respective front edge portions of said side wall members, each said framing member having a first edge portion formed in U-shape to receive in the throat thereof said front edge portion of a respective wall member and to embrace the same, each said framing member having a second edge portion spaced at a distance from said first edge portion and disposed adjacent said

20 respective wall member at said first vertical plane.

4. In a cabinet, the construction comprising opposite and spaced sheet metal side wall members, each said side wall member being recurrently bent back upon itself to provide horizontal channels inwardly of the cabinet bounded by a first vertical plane and a second vertical plane parallel to the first vertical plane, said side wall members at the front and rear edge portions thereof being disposed in a first of said vertical planes and said channels extending horizontally intermediate of said front and rear edge portions, metallic framing members for the respective front edge portions of said side wall members, each said framing member having a first edge portion formed in U-shape to receive in the throat thereof said front edge portion of a respective wall member and to embrace the same, each said framing member having a second edge portion spaced at a distance from said first edge portion and disposed adjacent said

30 respective wall member at first vertical plane, and vertically disposed right-angle metallic elements joined to the rear edge portions of said side wall members at said first vertical plane.

5. A sheet metal cabinet comprising side wall members each having channels formed therein by recurrent bends therein between spaced vertical planes, each of said side wall members having a front edge portion and rear edge portion along 40 the vertical edges thereof and disposed entirely in one of said vertical planes, a pair of metallic framing members disposed at said front edge portions of the respective side wall members, each said framing member being formed to receive and engage opposite sides of the front edge portion of a respective side wall member disposed in said one vertical plane and being formed to extend outwardly of the cabinet away from said first vertical plane and to extend toward said cabinet to join said wall member at said first vertical plane, and a rear wall member having vertical joining portions bent over at the vertical edges thereof to engage the rear edge portion of said side wall member at said first vertical plane.

6. A sheet metal cabinet comprising side wall members each having channels formed therein by recurrent bends therein between spaced vertical planes, each of said side wall members having a front edge portion and rear edge portion along the vertical edges thereof and disposed entirely in one of said vertical planes, a pair of metallic framing members disposed at said front edge portions of the respective side wall members, 50 each said framing member being formed to re-

70

75

ceive and engage the front edge portion of a respective side wall member disposed in said one vertical plane and being formed to extend outwardly of the cabinet away from said first vertical plane and to extend toward said cabinet to join said wall member at said first vertical plane, a rear wall member having vertical joining portions bent over at the vertical edges thereof to engage the rear edge portion of said side wall member at said first vertical plane, and a threaded fastening element disposed between each said framing member and respective wall member and joined to said framing member, said threaded fastening element being adapted to secure a bottom wall member to said cabinet.

7. A sheet metal cabinet comprising side wall members each having channels formed therein by recurrent bends therein between spaced vertical planes, each of said side wall members having a front edge portion and rear edge portion along the vertical edges thereof and disposed entirely in one of said vertical planes, a pair of metallic framing members disposed at said front edge portions of the respective side wall members, each said framing member being formed to receive and engage opposite sides of the front edge portion of a respective side wall member disposed in said one vertical plane and being formed to extend outwardly of the cabinet away from said first vertical plane and to extend toward said cabinet to join said wall member at said first vertical plane, a rear wall member having vertical joining portions bent over at the vertical edges thereof to engage the rear edge portion of said side wall member at said first vertical plane, a bottom wall member for said cabinet, and nut and bolt means for securing said bottom wall member to the cabinet, one of said means being carried by each said framing member and disposed intermediate the said each framing member and the respective side wall member.

8. In a cabinet, the construction comprising a sheet metal side wall member, said side wall member having its vertical front edge portion disposed in a first vertical plane and having a body portion alternately disposed in said first vertical plane and in a second and parallel vertical plane to form horizontal channels therein, and a metallic framing member disposed vertically and along said front edge portion, said framing member having a longitudinal groove opening toward said side wall member and disposed in said first vertical plane for accommodating therein, and embracing, said front edge portion and having a body portion extending, at an acute angle to said first vertical plane, outwardly from and hence inwardly toward said first vertical plane to define a longitudinal open space between said side wall member and said framing member, said framing member providing a rigid frame to said side wall member at said front edge portion.

9. In a cabinet, the construction comprising a sheet metal side wall member, said side wall member having its vertical front edge portion disposed in a first vertical plane and having a body portion alternately disposed in said first vertical plane and in a second and parallel vertical plane to form horizontal channels therein, a metallic framing member disposed vertically and along said front edge portion, said framing member having a longitudinal groove opening toward said side wall member and disposed in said first vertical plane for accommodating therein, and engaging opposite sides of, said front edge portion and having a body portion extending outwardly from and hence inwardly toward said first vertical plane to engage with said side wall member to define a longitudinal open space between said side wall member and said framing member, said framing member providing a rigid frame to said side wall member at said front edge portion, and a threaded stud positioned in said open space and joined to said framing member for securing another wall to said cabinet.

10. In a cabinet, the construction comprising a sheet metal side wall member, said side wall member having its front and rear edge portions disposed in a first vertical plane and having a body portion alternately disposed in said first vertical plane and in a second and parallel vertical plane to form horizontal channels therein, a metallic framing member disposed vertically and along said front edge portion, said framing member having a longitudinal groove in said first vertical plane opening toward said side wall member for accommodating therein and embracing said front edge portion and having a body portion extending outwardly from and hence inwardly toward said first vertical plane to said side wall member to define an open space between said side wall member and said framing member, said framing member providing a rigid frame to said side wall member at said front edge portion, and a rear wall member having a body portion and an edge portion bent over at right angles to the body portion and disposed in said first vertical plane, and joined to, the rear edge portion of said side wall member.
